UNITED STATES PATENT OFFICE.

WILLIAM HANLEY, OF CHICAGO, ILLINOIS.

SAFETY-GATE FOR RAILWAY-CROSSINGS.

SPECIFICATION forming part of Letters Patent No. 338,063, dated March 16, 1886.

Application filed July 18, 1885. Serial No. 171,933. (No model.)

To all whom it may concern:

Be it known that I, WILLIAM HANLEY, a citizen of the United States, residing at Chicago, in the county of Cook and State of Illinois, have invented a certain new and Improved Safety-Gate for Railway-Crossings; and I hereby declare the following to be a full, clear, and exact description of the same.

My invention relates to the class of gates now in quite common use upon the crossings of railroads, which all contain the feature of vertically-swinging bars upon posts, though the manner of actuating the bars differs very materially in the various gates belonging to the one genus; and it relates, particularly, to the means I employ to actuate the bars for the purpose of raising and lowering them and to the construction of the bars themselves.

A serious objection which attends the use of gates of the foregoing description consists in the fact that the mechanism used to cause the bars upon posts in line with each other upon the same side of a track to move in unison is commonly placed underground, which entails the inconvenience of tearing up the street for adjusting the mechanism originally and for repairing it whenever it gets out of order, as it frequently does from several causes, principal among which is the action of frost in winter. The wind also, when it blows with any material degree of force, affords a hitherto insurmountable obstacle to the properly smooth and regular movement of the gate-bars, as it exerts its force against their surfaces either longitudinally—*i. e.*, in the direction of the motion of one and in the contrary direction of that of its companion—or laterally, and thereby produces so much strain upon the parts as to seriously injure them in a comparatively short time.

It is my object to provide a construction of gate whereby these difficulties shall be avoided, and whereby a unique device shall be afforded, comprising great simplicity in its construction and mode of operation and entailing little expense for its manufacture.

To this end my invention consists in my construction of gate bar, and in the mechanism by which the gate-bars are actuated.

Referring to the drawings, Figure 1 represents one of my improved gates in elevation,

showing by dotted lines the position of the bars and controlling parts when the gate is closed. Fig. 2 is a perspective view of a bar of my improved construction pivoted between vertical standards forming a post, one side of which is broken away to display details of the bar, and Fig. 3 a top view of the windlass by means of which the bars are actuated.

A is a portion of a gate-bar formed, preferably, of a continuous piece of timber about two inches thick and twelve inches wide, but tapered toward one extremity, so as to decrease the width to about six inches. Transverse openings *t* are formed through the sides of the part A to render this portion of the gate-bar as light as possible, leaving braces *s* between the openings, and the rear extremity of the board so formed is mortised and secured by bolts, as shown, to the part A', comprising, preferably, a solid piece of wood sufficiently heavy to counterbalance the part A when the gate-bar is pivoted at its base to swing upon a post, C or C', as shown. If desired, instead of forming the part A of a single piece, it may be built of separate parts secured together to afford the construction represented. It will be seen that with this construction of the gate-bars they are not only rendered very light, whereby it need take but little power to raise and lower them, but the wind cannot interfere with their operation or in any way affect them materially, since it will meet with but little resisting-surface either on their narrow edges or on their sides, through which it is allowed to pass with but slight impediment.

Two bars are pivoted to form a gate through their bases, as shown, upon posts in line with each other upon the same side of a railroad-crossing, being adjusted to swing vertically toward and from each other. The posts may comprise each two parallel vertical standards, as clearly represented in Fig. 3, and may be provided with an inclosing-side at the rear, if desired; or any other suitable form of post may be employed. The minimum height of the posts must, however, be such as to come within municipal requirements in such matters and permit the ready passage underneath an imaginary line joining their upper extremities of all objects liable to move over the crossing.

Eighteen feet is considered to be the extreme height that will ordinarily be required for the posts.

To strengthen the parts A of the gate-bars which might otherwise be too much weakened by their construction hereinbefore described to serve their purpose under all conditions of the surroundings, I provide rods *r*, preferably of wood, having eyes *r'* upon their opposite extremities, and extending at right angles with the gate-bar through the braces *s*. Each rod *r'* projects the same distance on one side of the part A of the gate-bar that it does on the opposite side; but the rods are of varying lengths, that in the middle being the longest. A cable, *q*, is fastened at one extremity to the tapered extremity of the gate-bar on each side of the same, and extends backward through the eyes *r'* on the rods *r*, forming an angular line to the base A', where it is secured at its opposite end, a tightening-screw, *p*, of common construction forming a link in each cable for the purpose of permitting its tension to be regulated. This construction affords strength to the gate-bar, which thus may be constructed with a view to the attainment of lightness without being too frail.

Toward the upper end of the post C a cylindrical pulley, B, is secured to oscillate upon its bearings in a vertical plane, and a cable, *o*, secured at one extremity to one gate-bar toward the rear end of the part A' there of below the center of gravity of the gate-bar, passes around the pulley and proceeds from its under side over a small pulley, *n*, on the opposite post to the gate bar thereon, to which it is secured upon the part A above the center of gravity, and a similar cable, *o'*, is secured at one end to the part A' of the gate bar below the center of gravity of the latter on the post C', and extends over a pulley, *n'*, on the same post to the pulley B, over which it passes to the gate-bar on the post C, where it is secured upon the part A thereof above its center of gravity. It will thus be seen that the raising or lowering of the gate-bar on the post C will simultaneously raise or lower that upon the post C'. A windlass, D, is connected with the pulley B to operate the gate-bars by means of a rope, *D'*, which is wound at its center once from above around the barrel of the windlass, and is secured at each end upon the periphery of the pulley B at a point beyond a vertical line passed through its center when in its normal position with the gate-bars raised. Thus the left-hand strand of the cable *D'*, as shown in Fig. 1, would be fastened at its extremity to the point *x'* on the pulley B, and the right-hand strand at the point *x*.

The windlass D, which may be near the post C, as shown, or away from it, if desired, when the rope *D'* could pass from it to the pulley B over small pulleys suitably located, comprises a barrel portion, *m*, upon a shaft, *m'*, supported in a suitable frame, *k*, and operated by a winch, *i*. Two dogs, *l*, are piv-

oted to the frame *k* on opposite sides and toward opposite extremities of the barrel *m* to engage in contrary directions with ratchet-teeth *l'* around the shaft *m'*, one of which dogs 70 will always have to be raised when the windlass is to be rotated.

Since the pulley B has only to describe a quarter of a circle in raising or lowering the gate-bars, the windlass, to effect either operation with one complete revolution, need be only of a diameter equal to one-fourth that of the pulley, and the winch *i* may be constructed to provide a leverage which will permit the operation without great exertion. 80

As the cables *o* and *o'* are liable to become stretched with use, tightening-screws *p'* are provided upon each toward its fast end, whereby the slack produced may be taken up. 75

If it is desired to operate the gate-bars on the opposite side of a railroad-track simultaneously with those described, this may be effected by causing connecting cables to lead to them over suitable pulleys placed upon the post C, underneath the pulley B, and at a right angle to it, with which their ends could be connected. Ordinarily, however, it will be desired to employ a separate windlass for each gate when the gates can be operated independently of each other. Of course, in the latter case, the winches should be located in sufficient proximity to each other to permit both to be worked at the same time by the same operator. 90

What I claim as new, and desire to secure by Letters Patent, is—

1. A safety-gate for railway-crossings, comprising, in combination, vertically-swinging gate-bars mounted upon posts in line with each other on the same side of a railway-track, 105 pulleys *n* and *n'*, provided on one post, and a pulley, B, provided on another post, and cables passing over the said pulleys and connected to the several bars at opposite sides of the pivotal points thereof, whereby both bars 110 shall be raised or lowered simultaneously by raising or lowering one bar, as set forth.

2. A safety-gate for railway-crossings, comprising, in combination, vertically-swinging bars on posts in line with each other on the same side of a railroad-track, a pulley, B, on one post toward its upper extremity, and pulleys *n* *n'* on the opposite post, the cables connecting the said bars each attached at its opposite ends to opposite sides of the pivotal points of the bars and passing over the pulley B and pulleys *n* *n'*, and a windlass connected with the pulley B, whereby by turning the windlass in one direction the bars will be simultaneously lowered, and by turning it in the contrary direction the bars will be simultaneously raised, substantially as described. 120

3. A tapering gate-bar for safety-gates for railway-crossings, comprising the frame A, provided with transverse rods *r*, and cables *q*, connected longitudinally to the gate-bar and to the ends of the rods *r*, the solid base A', 130

sufficiently heavy to counterbalance the part A, and means, substantially as described, for regulating the tension of the cables.

4. A safety-gate for railway-crossings, comprising, in combination, posts C and C' in line with each other on the same side of a railway-track, a vertically-swinging bar mounted on each post, comprising a solid part, A', and a tapering frame, A, having transverse rods r, and cables q, connected longitudinally to the gate-bar and the ends of the rods r and provided with tightening-screws p, a pulley, B, secured to oscillate upon its bearings in a vertical plane upon the post C toward its upper end, a cable, o, secured at one end to the part A' of the gate-bar and passing around the pul-

ley B over a pulley, n, upon the post C' to the gate bar thereon, to which it is secured at the part A, a cable, o', secured at one end to the part A of the gate-bar on the post C, and 20 passing thence over the pulley B and over a pulley, n', upon the post C' to the gate bar thereon, to which it is secured at the part A', and a windlass, D, provided with dog mechanism l l' and connected with the pulley B by 25 means of a cable, D', the whole being constructed and arranged to operate substantially as described.

WILLIAM HANLEY.

In presence of—
MASON BROSS,
EDWARD THARPE.
